UNITED STATES PATENT OFFICE.

HARRY A. SHAW, OF CHICAGO, ILLINOIS.

COMPARTMENT-TRUNK.

1,244,647.

Specification of Letters Patent. Patented Oct. 30, 1917.

Application filed March 23, 1917. Serial No. 156,952.

To all whom it may concern:

- Be it known that I, HARRY A. SHAW, of Chicago, in the county of Cook and State of Illinois, have invented a new and useful Improvement in Compartment-Trunks; and I do hereby declare the following to be such a full, clear, and exact disclosure of its construction and operation as will enable others skilled in the art to make and use the same.
- 10 My invention relates to compartment trunks, and represents an improvement upon the trunk described and claimed in my U. S. Patent No. 1,175,478, granted to me March 14, 1916.
- 15 One object of my improved invention is to provide an easier access to the inside of the trunk, which object I accomplish by providing an additional door thereto, arranged opposite the first door.
- 20 A further object of my improved invention is to facilitate the withdrawal from the trunk of the frame which clamps and secures the articles packed therein, which object I accomplish by so constructing the frame as to permit its withdrawal bodily, thereby enabling one to make special selection of any given article and release the same from the clamp without disturbing any other article of clothing held by the 30 frame.
- A still further object of my invention is to provide a temporary support for the selected article while the frame is withdrawn from the trunk.
- 35 And a still further object of my invention is to so construct the compartment trunk and its appurtenant parts as to render its use easy and convenient and thoroughly adapted to the purpose intended.
- 40 These several objects are accomplished by the construction described by the following specification, illustrated in the accompanying drawing, and set forth in the appended claims.
- 45 It is well known that the requirements of modern travel necessitate the use of a packing trunk so constructed as to retain, as nearly as possible, the original shape and original condition of garments of personal 50 wear placed therein. In the use of the present construction of trunks, so far as applicant is aware, the wearing apparel packed therein for transportation is likely to become so mussed up and wrinkled in the ordinary handling of such trunks as to require that such apparel be smoothed by

pressing or otherwise, before it is again suitable for wear.

It is the purpose of my present invention to do away with this trouble for travelers, or, at least, to reduce it to a minimum for the traveling public.

And I carry out the above-mentioned purpose by constructing a trunk that is composed of a main body having two compartments and two doors oppositely located on said body and hinged thereto for easy opening and closing. One of said compartments includes several pockets of different sizes, with hinged doors fitted over the pockets, while the other compartment contains a sliding frame support with devices facilitating its movement into and out of the compartment.

In the drawings, wherein similar reference characters represent similar parts throughout,—

Figure 1 is a perspective view of the entire trunk with one door swung open and its pocket doors lowered.

Fig. 2 is a perspective view of the trunk with its opposite door swung open, disclosing the slidable frame support.

Fig. 3 is a detail of one of the upper corners of the trunk showing the adjustable support for the garment hanger.

Fig. 4 is a perspective view of the trunk with one door open and the slidable frame support withdrawn to its full extent.

Fig. 5 is an elevational detail of the 90 slid- able frame support and hanger.

Fig. 6 is a vertical section of the trunk on a line representing the vertical plane of the longitudinal center of each door as in Fig. 2 (with both doors closed) and with the hanger bars and their connecting rods omitted.

Fig. 7 is a detail of the adjustable releasing rods, and

Fig. 8 is a detail of the slide guide.

With reference to the drawing in detail,—

A designates the trunk in its entirety, divided longitudinally into two compartments, 1 and 2, which are severally closed by two oppositely arranged doors, A', B', respectively, each of which doors is hinged to its respective seat, and secured closed by means of the usual locks and latches.

The compartment 1 contains a hollow 110 rectangular frame, F, which fits tightly into and fills one face of the trunk. This frame

also forms a support for the ends and edges of the pieces 12, which extend laterally across said frame in parallel spaced relation, separating the frame into separate pockets 5 or compartments and supporting the doors by which said pockets or compartments are closed.

Each pocket is closed by a door which is hinged thereto at 13. Each door is operated 10 by a knob, C', which latter is connected with the ordinary spring latch shown conventionally at 14 in Fig. 1. By turning the knob of a closed door the spring latch can be operated in the usual manner to unlock the 15 door; and on closing the door, the spring latch will automatically lock it closed. There is no novelty claimed for this particular feature of knob and latch,—all of it being of the old and well known type, and, 20 therefore, the illustration is wholly conventional. Located beneath this door are two pockets G, one above the other, and at one side of these latter pockets and extending below the same is a vertical chamber H, for 25 receiving account books, ledgers, etc.

The uppermost door is designated by C, as in Fig. 1.

The chamber at the opposite side of said pockets G affords space for carrying hats, 30 bonnets, and the like, which articles may be supported on swinging brackets, as U, or on upright posts, as U'. A door Q is secured to the sides of one of the pockets and of the vertical chamber by means of 35 strips W, which latter are so arranged as to permit the door Q to be opened and closed by turning on its hinges 13.

When lowered in open position the door Q may serve as a writing desk. Below said 40 writing desk is a series of three pockets for clothing or other articles, said pockets being arranged in a vertical row, one above the other, and commanded, respectively, by three doors, I, J, and K.

45 After the pocket doors are closed, the door A' may be swung on its hinges to close the corresponding compartment. The trunk is provided with rollers R to facilitate its movement, and with an adjustably supported steadyng arm L to hold it against 50 accidental movement.

Compartment 2 is formed on the opposite side of the longitudinal partition P', which separates it from compartment 1, and constitutes the chamber in which the slidable frame support for the garments, is housed. 55 The said frame support is adapted to support the hangers for garments, and is composed of a skeleton constructed as follows:

60 A rectangular frame, composed of two vertical uprights, M and N, connected at top and bottom by two horizontal bars, m and n, respectively, constitutes the body of this frame.

65 Extending rearwardly in parallel spaced

relation from the top of said uprights are the rods o, which slide in sleeves o' and serve to steady the movement of said frame. Extending similarly from near the lower ends of said uprights are two flat bars p, p, which move in corresponding guides q', which are secured to the vertical walls of the compartment 2, and serve also to steady the movement of the frame.

Another upright, O, extends vertically 75 from the center of the horizontal bar, n, to the center of the horizontal bar m, to both of which bars said upright O is rigidly attached by any suitable means, and is provided with a central handle O'.

To the lower end of said upright O is pivotally attached a roll hanger block x, carrying roller y revolvably supported therein, and serving as a rotatable support for the center of the slidable frame.

To the upper end of the upright O is attached a sleeve o'', which slides upon a rod o''' extending forwardly from the partition P'. Said sleeve o'' is provided with a longitudinal slot in its upper side to fit over the upturned end of rod, o''', the said upturned end of the rod serving as an abutment to limit the outward movement of the sleeve.

Pendently supported from sleeve o'' are a number of rings, to which the garment 95 hangers h' are fastened by the hooks h'', which latter are each fastened to a coiled spring fastened to the hanger. These hangers, h', may be varied in number, and each is composed of an upper curved bar and a 100 lower straight bar, h'', which are connected together in vertical alinement by diagonally arranged cross rods r.

Attached to the under side of each of the curved bars of the hanger is a pair of trouser 105 supports, t, from which trousers are suspended.

Arranged in parallel spaced relation below the lower straight bars h'' of the hangers are a number of cylindrical sleeves, s, shown in detail in Fig. 7, each provided in its top with a slot s' for a purpose named hereinafter.

In these sleeves are housed a pair of sliding rods s', placed in alinement therein and 115 provided at their inner contiguous ends with corresponding thumb pieces s'', held apart by a coiled spring s''' and placed in sliding relation with the slot s'.

At their other end these bars s' extend 120 through the respective ends of the sleeve s and into perforations in the flat bars p, fitted in the guides q'. In this position the sleeves s are adapted to hold the hangers in a steady position by means of the rods r' which connect said sleeves s to said hangers. And when it is desired to disconnect any one hanger from the sliding frame support, it is only necessary to press down upon a given straight-bar h'' so as to remove the 125 130

tension, and then press the two thumb pieces toward each other, thus removing the two bars s' from their respective perforations in the flat bars p of the guides q' , when the 5 sleeve and its contained bars may be swung free and removed from the frame merely by detaching the hanger hook from its supporting ring.

A similar pair of sleeves and rods are 10 similarly arranged in compartment 2 below the last-named series of sleeves and rods, which operate in the same manner and for the same purpose as above described with reference to sleeve s and rods s' , respectively. This lower pair of sleeves and rods is located behind the upper sleeves and rods, and instead of being connected thereto by rods r'' , are connected to the lower ends of 15 a pair of upright frames f^2 , as shown in detail in Figs. 2 and 5. These upright frames are severally composed of two vertical bars connected at the top by a curved cross-bar f^3 , which latter is provided with a hook catching in a ring on the sliding sleeve o'' , 20 and also carries pendently therefrom a hanger, h' , for an overcoat, as seen in Fig. 4.

In this latter figure are also shown a 25 guide rod, 8, beneath which the lower end of the garment is passed, and a spring clamp, 9; for fastening down the lower end of said garment. Said spring clamp is composed of an inverted U-shaped rod, having its two 30 ends bent at right-angles to the body thereof and secured to a rotary shaft held in bearings on the floor of the sliding frame.

When a lengthy garment, as a coat, is to 35 be placed in the trunk so as to prevent its wrinkling in travel, the hanger is placed in the shoulders of said garment, as shown in Fig. 4, and the lower end of the garment is passed beneath the guide rod, 8, and then the edge thereof is clamped down by the 40 spring clamp, 9, which holds it flattened out and smooth on the floor of the sliding frame, thus keeping it intact until removed for use.

The guide rod is of an inverted U-shape 45 and is supported on a shaft carried at each end in the upturned edges of the floor 11, of the sliding frame support. Extending outwardly from the upper right-hand corner of compartment 2 as shown in Fig. 3 is a rest rod r^2 , which is pivotally attached to the inside wall of said compartment, and is 50 adapted to be swung outwardly before the sliding frame is withdrawn, and used to support a garment hanger which has been withdrawn from the sliding frame support.

The said rest rod, r^2 , is supported in a 55 bracket, r^3 , secured to the side wall of the compartment A. This bracket has a sleeve extension which is provided in its lower side with a cut-away portion forming a bayonet-joint locking shoulder for the down-turned 60 end of said rest rod. Normally the bent

upper portion of the said rod is pushed far enough through the bracket to swing clear of the slot therein, so that the long arm of the rod may hang down within the compartment, as indicated in dotted lines in Fig. 3. 70 But when required for use, the rod is swung upwardly to a horizontal position in its bearing in the bracket, and then pulled forward till its turned down upper end enters the cut-away portion of the bracket and is 75 thus locked against accidental turning.

From the foregoing description it is obvious that my improved trunk is adapted to hold a variety of garments of wearing apparel intact and free from the possibility of 80 wrinkling or crumpling in transportation, and the method of using the trunk is also obvious.

In the case of wearing apparel the garments are placed upon any one of the hangers h' , after the latter has been detached from the sliding frame support in the manner hereinbefore described. The hanger is then reset in the frame by attaching its hook to a ring depending from the sleeve 85 o'' . The body of the garment is then smoothed out between contiguous diagonal rods of two adjoining hangers, and in case the garment is not long enough to extend to the parallel sleeves s , its lower end may be 90 caught by the clipping dogs $13'$ on both ends of the horizontal bars h^2 , and thus held intact. 95

As many garments may thus be packed together as there are hangers to support them, 100 and, if properly placed in the trunk, each garment can be taken therefrom in as good condition as when placed therein. If the garment to be packed is long enough, the lower portion thereof may be passed down through 105 the guide rod 8 and its lower edge pressed to the floor by the spring clamp 9, thus holding the whole length of the garment in a straight and smooth condition.

Although I have illustrated and described 110 my invention with some particularity, I am aware of the fact that various changes thereof may be made in the practical application of it, and for this reason I reserve the right to change or modify the form of the details 115 of construction, or otherwise alter the arrangement of parts without departing from the spirit or enlarging the scope of the attached claims.

Having thus fully described my invention, what I claim as new and desire to secure by Letters-Patent is:

1. The combination, in a compartment trunk, of a slidable frame support fitted to slide into and out from said compartment, 120 with garment hangers supported on said slidable frame and provided with means for adjusting said hangers to position in the frame and holding the hangers and the contained garments taut therein, said means in- 125 130

cluding supporting hooks attached to the central upper rod of the frame and spring connections between said hooks and hangers for attaching the hangers to the frame, and 5 spring-impeled parallel rods spaced apart for fastening the hangers to the sides of the frame by means of inclined rods connecting said parallel rods and hangers, substantially as described.

10 2. In a sliding frame support for the garment hangers of a compartment trunk, a skeleton frame composed of two upright bars connected at top and bottom by transverse rods, and provided at their upper ends 15 with rods sliding in tubular members fastened in the upper end of the compartment, and said uprights also being provided at their lower ends with two flat bars sliding in guides fastened in the lower end of the 20 compartment; a third upright connected at its top and bottom to the central portions of the upper and lower transverse bars, respectively, of said frame, and carrying at its top an inwardly extending sleeve provided 25 with a series of rings to support garment hangers, and at its lower end an adjustable roller adapted to support the lower end of the sliding frame in its movement into and out from the compartment; a floor located

at the bottom of said sliding frame support 30 and provided with means for keeping the lower end of a garment taut and extended in flat, smooth condition, substantially as described.

3. The combination with a trunk having 35 guide plates on the walls of a compartment thereof, of a sliding frame support, said support comprising flat bars having sliding engagement with said guide plates, a plurality of hangers, yieldingly supported from 40 a rod in the said frame, a plurality of bars h^3 , placed below the hangers and connected thereto by a plurality of diagonally disposed rods, r ; the said bars, h^3 , being connected to a releasing device, the latter comprising 45 a tubular sleeve provided with a longitudinal slot arranged centrally in its upper side, a pair of releasing rods carried by said tubular sleeve and arranged in alignment, each of said rods having at its inner 50 end a thumb or finger piece extending through the slot in the sleeve, and the outer end of each rod extending through the sleeve and into perforations in the flat bars of the guide plates on the walls of the compartment. 55

HARRY A. SHAW.
